UNITED STATES PATENT OFFICE.

JONATHAN HILL, OF JERSEY CITY, NEW JERSEY.

DESIGN FOR A BELT-FASTENER.

SPECIFICATION forming part of Design No. 27,262, dated June 29, 1897.

Application filed April 30, 1897. Serial No. 634,645. Term of patent 14 years.

To all whom it may concern:

Be it known that I, JONATHAN HILL, a citizen of the United States, residing at Jersey City, in the county of Hudson and State of New Jersey, have invented and produced a new and original Design for a Belt-Fastener, of which the following is a specification, reference being had to the accompanying drawing, forming a part thereof, in which the figure of the drawing is a perspective view of a belt-fastener embodying the features of my design.

The design consists in an arched bar A, the ends *a* whereof curve over the body in opposite directions.

15

I claim—
The design for the belt-fastener herein shown and described.

JONATHAN HILL.
